UNITED STATES PATENT OFFICE.

EDWIN F. GUTH, OF ST. LOUIS, MISSOURI.

LIGHTING FIXTURE.

Application filed May 29, 1920. Serial No. 385,360.

To all whom it may concern:

Be it known that I, EDWIN F. GUTH, a citizen of the United States of America, residing at the city of St. Louis, State of Missouri, have invented a certain new and useful Lighting Fixture, of which the following is such a full, clear, and exact description as will enable any one skilled in the art to which it appertains to make and use the same, reference being had to the accompanying drawings, forming part of this specification.

My invention relates to a novel lighting fixture for enclosing lamps of high brilliancy and at the same time efficiently utilizing the light therefrom.

In the accompanying drawings, Fig. 1 is a view in partly cross sections and partly in elevation of a lighting fixture embodying my invention and Fig. 2 is a bottom plan view of one half of the light controlling and diffusing member suspended beneath the light source.

1 represents an opaque and preferably parabolic reflector enclosing the light source. 2. In the form shown the reflector is supported from the lamp socket but it may, of course, be supported in any other suitable manner. 3 is a plate of translucent material, preferably diffusing glass, suspended beneath the reflector opening and of larger diameter than said opening. The central portion of this plate is cone shaped with the apex of the cone upward and the outer part is in the form of an upwardly inclined flange, whereby a portion of the reflected light from the source is reflected outwardly, a part of it passing between the plate and the lower edge of the reflector and a part of such of said reflected light as is intercepted by the outer flange portion of the plate being reflected upwardly to light the ceiling in the vicinity of the fixture support and thus prevent the formation of a shadow of the upper part of the fixture on the ceiling. Another function of the cone shape arrangement of the central portion of the plate is that the most highly illuminated portion of the plate, which of course is the central portion is not in view when the fixture is

observed from the usual angles and the appearance of the fixture when used for lighting is better than if some of the observable portions thereof were more brilliantly illuminated than others.

In my fixture all of the visible light is diffused and the brilliancy of the illuminated portions of the fixture is low, while at the same time the total light of the source is controlled and transmitted in an efficient manner. The parabolic reflector emits reflected rays in parallel lines and the distribution of these rays is to a large extent controlled by the inclination of the conical surface of the central portion of the diffusing plate.

By preferable construction the parts will be so assembled that the upwardly inclined flange of the diffusing member will extend above a straight line passing through the light source and the lower edge of the reflector.

Having fully described my invention, what I claim and desire to secure by Letters Patent of the United States is:

1. In a lighting fixture, the combination with a source of light of a reflector enclosing said source and opening downwardly, a light reflecting and diffusing member positioned beneath and spaced from the reflector opening and of greater diameter than said opening, said diffusing member having its central portion cone-shaped and its outer portion in the form of an upwardly inclined flange.

2. In a lighting fixture the combination with a source of light of a reflector enclosing said source and opening downwardly, a light reflecting and diffusing member positioned beneath and spaced from the reflector opening and of greater diameter than said opening, said diffusing member having its central portion cone shaped and its outer portion in the form of an upwardly inclined flange extending above straight lines passing through the light source and the lower edge of the reflector.

In testimony whereof, I have hereunto set my hand and affixed my seal.

EDWIN F. GUTH. [L.S.]
